RADIO TUNING SYSTEM

William H. Hoffman, Bloomfield, N. J., and Donald H. Mix, Hicksville, N. Y., assignors to Burgess Battery Company, Madison, Wis., a corporation of Wisconsin

Application April 14, 1930. Serial No. 444,124

11 Claims. (Cl. 250—40)

This invention relates to systems for radio communication, particularly to the receiving portion of such systems. More especially the invention relates to radio receivers designed for reception of signals in the so-called "short-wave" region embracing a relatively wide range of frequencies extending upward from about 3,000 kilocycles.

A primary object of the invention is to provide a unitary tuning mechanism for a receiver of the type specified which permits accurate tuning over a wide range of frequencies as compared to the tuning range of the usual broadcast receiver, such, for example, as the short-wave region extending from 3,000 to about 20,000 kilocycles, without the necessity for changeable inductance coils or any other alteration inside the receiver.

It is a further object of the invention to provide a unitary tuning mechanism comprising a coarse tuning element which is continuously variable over the short-wave region and serves to adjust a fine tuning element associated therewith to operate within a relatively narrow selected frequency band, said fine tuning element being thereafter operable to select a particular frequency within said band.

Other objects are to provide a radio-frequency amplifier or a complete radio receiver which is continuously tunable at a relatively slow rate of frequency change over a wide range in frequency as compared to the usual broadcast receiver; as well as to provide a short-wave "adapted" for adapting any standard broadcast receiver to operate over the short-wave region.

If desirable, the tuning mechanism may be designed to provide substantially straight line frequency tuning over the entire tuning range.

In the design of a radio receiver suitable for short-wave reception certain problems must be solved which are not encountered in receiver design for the ordinary broadcast range. In the first place, whereas the broadcast region covers the relatively narrow frequency band extending from about 500 to 1500 kc., the short-wave region at present extends from 3,000 to about 20,000 kc. In the second place, the close allocation of broadcasting frequencies within the short-wave region necessitates the use of a receiver which is highly selective over the entire frequency spectrum and hence one in which the frequency of tuning varies at a relatively slow rate with adjustment of the

tuning elements. Thus, the short-wave receiver must be tunable over a frequency band which is about eleven times as wide as the broadcast band, and yet it must tune more slowly than the broadcast receiver due to the crowding of amateur channels in the short-wave region.

As regards the tuning adjustment of the receiver, experience has taught that most satisfactory tuning is obtained by use of a variable capacity in shunt with a fixed inductance. This applies to short-wave tuning as well as the usual broadcast range. But whereas in the broadcast range it is a fairly simple matter by the use of a single fixed inductance shunted by a single variable capacity operating between certain maximum and minimum capacity values to obtain a tuner which will tune over the entire broadcast band of 500 to 1500 kc., tuning over the short-wave band is not so simple, due to the wide range of frequencies to be covered.

Assuming the inductance to be fixed, the resonance frequency is inversely proportional to the square root of the tuning capacity. Or, expressed in a slightly different manner, the maximum and minimum resonance frequencies are related to the corresponding limiting values of capacity in accordance with the equation

$$(1) \quad \left(\frac{F_{\max.}}{F_{\min.}} \right)^2 = \left(\frac{C_{\min.}}{C_{\max.}} \right)$$

In the broadcast range this ratio amounts to only 9:1 whereas over the short-wave region it becomes about 45:1. Inasmuch as the minimum capacity of a condenser is in general beyond control, being determined by certain physical limitations, it will be obvious that to provide a single capacity capable of tuning satisfactorily over the entire short-wave region would be impracticable.

Accordingly, it has been the practice in constructing short-wave receivers to provide a multiplicity of plug-in type inductances, each adapted when connected in shunt with a standard variable condenser to permit tuning over a small portion of the short-wave region, sufficient coils of successively increasing inductances being thus provided to cover the entire short-wave band.

But here again further difficulties are immediately encountered. Since as pointed out, the tuning range covered by a given condenser is a function of its minimum and maximum capacity

values, when a variable condenser of the ordinary type is used one always runs into the difficulty of unequal frequency span between the high and low frequency ends of the receiver range. A condenser which is small enough to tune nicely at 15,000 kc. will tune unnecessarily slowly at 3,000 kc., and furthermore requires the use of a large number of plug-in coils because of the successively smaller ranges covered by the condenser as the receiver is adjusted to lower frequencies. In case the tuning condenser is made large enough to tune satisfactorily at 3,000 kc., only a few plug-in coils will be required, but as the receiver is adjusted to the higher frequencies, the frequency coverage will become so great that successful tuning of a sharp signal will become almost impossible.

By way of example, suppose a condenser to be selected having its maximum to minimum capacity in the ratio of 9:1; such a capacity will cause a frequency variation of the order of 1:3. With a given coil connected in shunt it may be assumed that at the initial capacity setting the frequency of tuning is 1,500 kc. The capacity being increased to its maximum value the frequency of tuning will be reduced to 500 kc. The difference is 1,000 kc. With a different coil the tuning frequency at minimum capacity setting may be assumed at 15,000 kc. An increase of capacity to its maximum value will reduce the resonant frequency to 5,000 kc., a difference of 10,000 kc. In other words, with each different coil, equal displacements of the adjustable element of the condenser produce unequal changes in the tuning frequency, and thus the "speed" or rate of tuning is said to be different. The greater the frequency change for a given change in capacity, the higher is the rate of tuning. When the rate of tuning is high it is, of course, difficult to tune accurately, since a very slight adjustment of the tuning element will effect a material change in frequency.

The present invention provides a tuning device for short-wave tuning which overcomes all of the aforementioned difficulties and in addition embodies added desirable features. The specific tuning system disclosed covers all frequencies from 3,000 to 20,000 kc. without the use of plug-in coils or the necessity of any other alteration inside the receiver. This has been done without sacrificing the sensitivity of the receiver. At no place over the entire frequency range does the tuning "speed" or rate of tuning exceed a range of substantially 1,500 kc. per 180° dial movement of the fine tuning element so that the system tunes in substantially the same manner as present-day broadcast receivers. Furthermore, over the entire tuning range extending from 3,000 to 20,000 kc. the tuning is exceptionally close to straight-line frequency tuning.

Broadly speaking, the invention accomplishes the above mentioned objects by providing a tuning mechanism consisting of coarse and fine tuning members arranged to cooperate in a certain manner. The coarse tuning member is a resonance circuit comprising variable inductance and capacity elements in parallel electrical connection. The fine tuning member is connected in additive electrical relation to the device of similar character in the coarse tuning member. That is, if the fine tuning member is a capacity, it is connected in parallel with the capacity of the coarse tuning member, whereas if it is an inductance, it is connected in series with the inductance of the coarse tuning member.

The fine tuning member comprises two cooperative movable elements, the first being independently movable for fine tuning, the second being positively mechanically controlled by the control adjustment of the coarse tuning member. The reactances of the coarse tuning member are thus adjusted conjointly with the second element of the fine tuning member. This positive relation between positions of coarse and fine tuning elements makes it possible to so design the latter that for all settings of the coarse tuning member, the frequency ranges covered by movement of the fine tuning member from minimum to maximum setting will be approximately equal.

In the specific embodiment of the present invention the tuning device is composed of three separate items all mounted as a single unit, preferably on a small panel of insulating material. It comprises an inductance in the form of a small variometer. In shunt with the variometer is a "midget" or "micro" type of variable capacity of about 135 micro-microfarads maximum capacity. In shunt with this capacity is another variable capacity of special design in which both rotor and "stator" plates are movable. The operation of the device in general is as follows: The variometer and "micro" condenser tune the circuit to approximately the desired frequency while the special condenser acts as a vernier capacity of variable maximum to minimum capacity ratio and tunes over the desired band.

A uni-control device is provided for simultaneously adjusting the variometer, the micro-condenser and the "stator" plates of the special condenser, the latter operation being required to select the proper maximum to minimum capacity ratio for the special condenser to permit tuning over the desired frequency band based on the rough tuning adjustment. This may, of course, be accomplished by mounting all of the elements in question upon a common shaft, or as is disclosed specifically in the present instance, by linking the shafts of the various elements together by means of a system of belts and pulleys. This arrangement constitutes a "shift" dial arrangement by means of which the operator may shift to any one of 13 overlapping frequency bands at will within a fraction of a second, thereby covering the entire short-wave region. The rotor plates of the special condenser are turned by the second dial which constitutes the usual tuning control for selecting a desired frequency within a given band. The plates of the special condenser are so designed that whatever the position of the shift dial the frequency range covered by adjustment of the rotor plates remains substantially constant at about 1500 kc. per band.

As embodied in a radio receiving system, the variometer may be provided with a stationary tickler winding for regenerative purposes. It is a feature of this arrangement that the necessity for wide variation in oscillation control often found in short-wave receivers of wide tuning range is practically eliminated, since the coupling between the variometer windings and the tickler automatically increases or decreases respectively as the inductance of the variometer nears its maximum or minimum values.

The special condenser is so designed that for any position of the stator plates, adjustment of the rotor plates through an angle of 180° will adjust the tuning frequency over a band of substantially 1500 kc. This result is obtained by carefully shaping both the rotor and stator plates to cause the interleaving area to be varied in ac-

cordance with the setting of the stator plates as well as in accordance with the position of the rotor plates. The proper proportioning of the rotor and stator plates is obtained from a consideration of the fact pointed out above that the ratio of maximum to minimum frequency varies with respect to the point in the frequency spectrum at which it is desired to pick off a particular band of 1,500 kc. over which adjustment of the 10 rotor plates will tune the circuit. For example, in a change from 20,000 to 18,500 kc. the ratio of frequency variation is in the proportion of 1.08:1, while in a change from 4,500 to 3,000 kc. the corresponding ratio is in the proportion 1.50:1, and 15 at all intermediate points on the frequency scale the ratio varies between these two elements. From this data it is possible to calculate if it be desired to cover a frequency range of 20,000 to 3,000 kc. in steps of 1,500 kc., that the tuning condenser must have a variable ratio of its minimum to maximum capacity such that the ratio may be set at any desired value between the elements $(1.08)^2=1.166$ and $(1.50)^2=2.25$.

In order that a fair value of inductance may 25 be used for the variometer, the special condenser must be of such design that 180° dial movement causes very small areas of rotor and stator plates to become interleaved at the high-frequency end while a corresponding dial movement at the low-frequency end must cause relatively large areas 30 of rotor and stator plates to become interleaved. This is accomplished, of course, by suitably shaping the rotor and stator plates, and by providing means for shifting the interleaving portion 35 of the stator as compared to the rotor plates.

Since it is undesirable both from the standpoint of mechanical simplicity and electrical efficiency to use a small inductance and cover the entire frequency range by means of a large capacity, use has been made of the variometer in order 40 to insure that regardless of the portion of the frequency band over which the set is being operated, there is a fair proportion of inductance to capacity in the circuit.

45 Likewise, it is desirable to have a certain amount of minimum capacity in the circuit when working at the lower frequencies where it is possible to use it. This is supplied by means of the "micro" condenser in shunt with the variometer.

50 Having thus described the invention in general terms, reference will now be had to the drawings for a detailed description of a specific embodiment thereof which has proved highly satisfactory in actual practice for short-wave reception.

55 Referring to the drawings, Figure 1 gives a plan view showing the assembly and mechanical details of a tuning device in accordance with the present invention.

Figure 2 shows a side elevation as viewed from 60 the right in Figure 1. To avoid confusion, the fragments of condenser C which are visible, are omitted.

Figure 3 shows a section along the line 3—3 in 65 Figure 1, except that a midsection of the stator of variometer A is shown.

Figure 4 shows in circuit diagram form an application of the invention which may be utilized 70 as a short-wave receiver or as an "adapter" for adapting the usual type of broadcast receiver to short-wave reception.

Figure 5 shows in circuit diagram form a complete multi-stage short-wave receiving system 75 wherein the tuning is accomplished by means of the special tuning device of the present invention.

Like elements are similarly designated in the several views.

Referring more especially to Figures 1-3 inclusive, the tuning mechanism comprises the variometer A, "micro" condenser B, and the special condenser C, all suitably mounted upon a single panel 1 of insulating material.

The special condenser C comprises two complementary units R₁ and R₂, each consisting of a set of condenser plates N mounted upon a shaft S rotatably supported within a housing 3 upon journal bearings 8 affixed to conductive end plates 5 which latter are suitably positioned in rigid assembly and spaced relation by means of spacing members 6 and screws 7. Lock nuts 4 may be provided to longitudinally adjust the condenser plates.

The units R₁ and R₂ are rigidly mounted between insulating members 9 and 10 by means of screws 11 with shafts S parallel and in such manner as to permit interleaving of plates N₁ of unit R₁ with plates N₂ of unit R₂. Conductors 12 may be added to insure positive electrical connection between the shafts S and end plates 5. The units R₁ and R₂ are, of course, insulated from each other due to mounting between the insulating members 9 and 10.

It is usually preferable to limit the angular movement of plates N to 180°, and to this end each shaft S is provided with a pin 13 adapted to engage stops 14 and 15 (see Figure 3) affixed to end plates 5.

The condenser structure is mounted upon panel 1 by means of spacing members 16 and bolts 17. Shaft S₂ extends through the panel being fitted 110 at its outer end with a pulley P₁ of insulating material for purposes explained below. Shaft S₁ likewise extends through panel 1 and also through a second panel 18 which constitutes a portion of a cabinet in which the structure is housed, the 115 shaft being provided at its outer end with a graduated dial D₁ for adjusting the plates of condenser unit R₁. A stationary marker on panel 18 cooperates with dial D₁ to indicate the adjustment of unit R₁.

It will be observed from Figure 3 that the condenser plates of units R₁ and R₂ are so shaped that for a given setting of unit R₂ the rotation of unit R₁ counterclockwise between stops 14 and 15 will produce a gradual increase in the interleaving area of plates N₁ and N₂ thereby producing a variation of capacity which changes from a certain minimum to a certain maximum value. It will be observed further that successive adjustments of plates N₂ in a clockwise sense afford 125 successively increasing maximum interleaving areas between plates N₁ and N₂ thereby increasing the ratio of maximum to minimum capacity of the condenser. It will thus be seen that by 130 suitably positioning the condenser plates N₂ corresponding to a frequency band over which it is desired to tune, that the same "speed" of tuning due to adjustment of dial D₁ may be obtained over a frequency band of given width such as 1500 kc. irrespective of the allocation of the band with- 140 in the short-wave region.

The unit R₂ corresponds to the stator element of the usual variable condenser while the unit R₁ corresponds to the rotor element. The "stator" unit R₂ is in this instance variable in order to 145 permit adjustment of the ratio of maximum to minimum for a 180° movement of plates N₁.

The "micro" condenser B also mounted upon the panel 1 comprises a set of stator plates 35 and a set of rotor plates 36. The condenser unit 150

is affixed to the front of panel 1 by means of an externally threaded bushing 37 which passes through the panel being held in place by means of a lock nut in the manner well known in the art. A pulley P_2 is mounted upon the outer end of rotor shaft S_3 of condenser B which shaft projects through the panel 1.

The variable inductance or variometer A consists of a coil 20 rotatably mounted within stationary coil 21. The stationary coil 21 is mounted, as shown more clearly in Figures 2 and 3 upon the inner periphery of a ring 22 of suitable insulating material. The movable coil is wound upon a second ring 24 of insulating material which is rigidly mounted upon shaft S_4 whereby rotation of the shaft produces angular displacement of coil 20 relative to coil 21. Pulleys P_3 and P_4 are fitted to the portion of shaft S_4 projecting through panel 1, while a dial D_2 is affixed to the outer end of the shaft which projects through the cabinet panel 18. This dial likewise cooperates with a stationary indicator affixed to the panel 18 whereby the position of adjustment is indicated.

25 A belt 27 extends over pulleys P_1 and P_3 being affixed thereto respectively by means of screws 28 and 29 to provide a positive drive. Likewise a belt 30 passes over pulleys P_2 and P_4 being affixed thereto respectively by means of screws 31 and 32 to provide a positive drive. It will thus be seen that adjustment of dial D_2 simultaneously varies condenser unit B, the variometer A and the "stator" element R_2 of the special condenser C. On the other hand, adjustment of dial 35 D_1 varies the position of the rotor element R_1 of the special condenser C independently of the position of the stator element S.

The external electrical connections of the various elements are not shown in Figures 1 to 3, 40 but are shown in the circuit diagram drawings of Figures 4 and 5.

Coarse tuning to select the frequency band of 1500 kc. within which it is desired to select a particular frequency is accomplished by adjustment of dial D_2 . By means of the pulleys and belts heretofore described, the adjustment of dial D_2 causes motion to be transmitted to shaft S_2 of condenser C and shaft S_3 of condenser B, the variometer A, of course, being directly operated. 45 In this manner the variable elements thus connected together are caused to maintain a predetermined established relationship in all conditions. Having selected the frequency band within which it is desired to tune by adjustment of dial D_2 , the particular frequency to be selected 50 within the band is then obtained by operation of dial D_1 which provides the fine tuning adjustment by means of rotor unit R_1 . The predetermined established relationships between the positions of the movable elements of reactances A and B and shaft S_2 of condenser C, make it possible to so design the reactances, as will be explained hereafter, that for all settings of the coarse tuning member, equal angular displacements of the fine tuning member R_1 cause substantially equal changes in the resonance frequency of the tuning mechanism.

Straight line frequency tuning of circuits comprising inductance and capacity are built on the general principle expressed in the following equation, which is chosen arbitrarily to cover the case where frequency decreases as angularity increases:

$$75 \quad (2) \quad \theta = \theta_0 - K \left(\frac{1}{\sqrt{LC}} - \frac{1}{\sqrt{L_0 C_0}} \right)$$

Where L and C represent the inductance and capacity corresponding to an angular adjustment θ of the tuning element from its initial setting θ_0 at which the inductance and capacity values are L_0 and C_0 respectively. If the adjustment of the tuning element is such as to vary the capacity only the equation reduces to the simpler form:

$$80 \quad (3) \quad \theta = \theta_0 - \frac{K}{\sqrt{L_0}} \left(\frac{1}{\sqrt{C}} - \frac{1}{\sqrt{C_0}} \right)$$

85 Both inductance and capacity may be caused to vary together to meet the conditions represented by the Equation (2) but the usual practice is to vary the capacity only in accordance with Equation (3). To cover the short-wave frequency range by means of a single tuning circuit having straight line frequency characteristics either the capacity and inductance would have to assume excessive size, or the tuning would be too rapid for accurate adjustments at any point. The present invention overcomes such objection.

90 The shape of the plates N_1 of the fine tuning member of the special condenser C resemble somewhat the shape of ordinary straight-line tuning condensers, and are designed upon the 100 consideration stated that in a resonant circuit with the inductance remaining constant, the resonance frequency varies inversely as the square root of the capacity. Considering therefore a single setting of the coarse tuning dial D_2 , 105 the special condenser must have its plates N_1 so shaped that the square root of the capacity of the entire system varies inversely as the angular displacement of the fine tuner control dial D_1 .

95 The shape of the second set of plates N_2 must 110 be such that as the coarse tuner dial D_2 is moved to lower frequency settings, a greater maximum surface area is presented to plates N_1 . The plates are further so shaped that at the lower frequency settings of plates N_2 the rate of change 115 of interleaved surface of plates N_1 and N_2 is more rapid for equal angular displacements of the fine tuning member than it is at the higher frequencies. This increased rate of change of interleaved surface at the lower frequencies is obtained largely by increasing the width of the stator plates N_2 toward the low-frequency settings in such manner that upon advance of plates N_1 the foremost portions of the plates N_1 will not project beyond the plates N_2 as they do at 120 the higher frequency settings, but at the low frequency settings substantially all of the surface area of plates N_1 and N_2 which once becomes interleaved remains interleaved during continued rotation of plates N_1 toward the low-frequency 125 end of the band.

130 In the specific embodiment as shown in Figure 3 plates N_1 as well as plates N_2 are of J-shaped configuration, this shape being chosen for practical reasons, namely to make possible 135 the use of the same set of dies for both sets of plates, thereby simplifying and reducing the cost of manufacturing operations. However, from Equation (3) above it is readily appreciated that plates N_1 and N_2 may take a variety of shapes dependent upon the design of the inductance and capacity of the coarse tuner, as well as upon the consideration that either of them may be maintained constant during coarse tuning.

140 It will also be noted that with plates N_1 remaining in their initial position, as shown in Figure 3, movement of plates N_2 from their initial setting causes some interleaving of the two sets of plates. In the position shown, plates N_2 are at their mid-setting but the area interleaved is 145 150

very slight. This area increases as plates N_2 are moved angularly in a clockwise direction, but even at their final setting, it is not considerable. In fact, the capacity changes due to the 5 leaving caused by movement of plates N_2 are practically negligible when compared with the capacity of micro condenser B at corresponding settings and ordinarily need not be taken into account in the design of the mechanism.

- 10 The design may be changed so that no interleaving results from movement of plates N_2 , assuming plates N_1 in their initial position as shown in Figure 3. Practically all of the coarse tuning is accomplished by means of condenser B and inductance A, and all fine tuning by means of the special condenser C. It is possible to so 15 design the tuning mechanism that movement of plates N_2 from their minimum setting causes appreciable interleaving with plates N_1 and the capacity changes caused thereby may be considered as assisting in the coarse tuning and taken 20 into consideration when designing the coarse tuner; that is, plates N_2 may thus become a part of the coarse tuner.
- 25 To simplify construction, the coarse tuning elements may, of course, all be mounted upon a common shaft, in which case the pulleys and belts could be omitted. For example, the rotor element of condenser B and the movable coil 30 20 of the variometer A could all be mounted upon an extension of shaft S_2 carrying the stator plates N_2 of the special condenser.

- To further simplify construction it might prove expeditious to combine the special condenser C 35 and the micro condenser B into a single condenser which would be similar to condenser C except that the plates thereof would have additional interleaving surface to supply the capacity furnished by condenser B, which additional surface could be arranged to be brought into operation by manipulation of the coarse tuning control.

The circuit diagram of Figure 4 illustrates the manner in which the short-wave tuner of the 40 present invention may be embodied in a radio receiver, or in a short-wave "adapter" for adapting an ordinary broadcast receiver to short-wave reception. The tuning mechanism is enclosed within the dotted rectangle T wherein it will be 45 obvious that the variometer, special condenser and vernier condenser are connected in parallel electrical relation. The dashed lines L indicate the uni-control feature whereby the coarse tuning adjustment is obtained, while the lower plates 50 of the special condenser C are indicated as being independently variable to accomplish the fine tuning adjustment.

The input circuit of the tuning device T is 55 connected at its opposite terminals through a condenser 42 to antenna 43 and to ground 44 respectively. The output terminals of the tuning element are connected through a grid condenser and leak resistance 45 to the grid electrode and to the cathode respectively of a vacuum tube V which in this instance is indicated as being of the heater element type.

It was previously stated that pulley P_1 is of 60 insulating material. The reason for this is apparent from Figure 4 wherein it is to be noted that pulley P_1 controls unit R_2 of the special condenser which is connected to the high potential side of the tuning circuit. If the fine tuning element R_1 were connected to the grid electrode of tube V instead of the stator element R_2 , tuning

would be rendered difficult due to the effect of body capacities.

If the circuit of Figure 4 is to be embodied in a complete radio receiver, terminals E₁, E₂ and E₃ are connected respectively to terminals F₁, F₂ and F₃ whereby a source of current 47 is applied to the heater element of tube V, and headphones 48 and a space current supply source 49 are serially interposed in the plate circuit of the tube.

If, on the other hand, it is desired to utilize the circuit as an "adapter" for adapting an ordinary broadcast receiver to short-wave reception, terminals E₁, E₂ and E₃ are connected respectively to terminals H₁ and H₂ and H₃ which terminals in turn are joined by means of conductors 50 to the heater element and plate prongs of a plug 51 adapted to be inserted in the detector tube socket of the broadcast receiver. With such an arrangement the radio-frequency waves impinging upon the antenna 43 are selected and detected by means of the circuit of Figure 4, and are then passed through the contacts of plug 51 to the detector output circuit of the broadcast receiver and thence 100 through the audio-frequency stages thereof to the receiving element. With such an arrangement the broadcast receiver, of course, supplies the necessary heating current and space supply current for operating the tube V of the 105 "adapter circuit" of Figure 4. With the broadcast receiver connected to the adapter circuit in this manner, the radio-frequency stages of the broadcast receiver are, of course, ineffective due to the fact that the lead which normally extends to the grid electrode of the broadcast receiver detector tube is open.

For greater practical success, refinements may be included in the circuit of Figure 4. For example, the output and input circuits of the detector tube V may be regeneratively coupled as by means of the tickler coil 52 placed in inductive relation with the variometer A. The condenser 53 and variable resistance 54 in series may be connected across the output circuit of the 115 detector tube to control regeneration. A radio-frequency choke coil 55 may be serially interposed in the plate circuit to choke out the radio-frequency currents therefrom, and variable resistance 56 may also be included to permit adjustment of the plate voltage, in which event it is desirable to shunt the resistance with a condenser 57 in order to reduce electrical disturbances resulting from adjustment of the resistance.

Figure 5 shows diagrammatically a complete short-wave receiver employing a unitary tuning device T₁ in accordance with the present invention for coupling an antenna circuit 60 to the input of a screened grid vacuum tube V₁ operating as a stage of radio-frequency amplification. A second unitary tuning device T₂ serves to couple the output of tube V₁ to the input of a second tube V₂ adapted by means of the series capacities 61 and shunt resistance 62 to operate as 135 a detector for rendering the radio signals audible. The detector output is connected through two stages of audio-frequency amplification comprising transformers P₁ and P₂, vacuum tubes V₃ and V₄ to a pair of headphones or other 140 receiving element 40.

Battery B₁ which may be tapped at suitable potentials serves to provide space current for the several tubes, and also a suitable potential to the screen grid of tube V₁. The filaments of the 150

tubes are heated by battery B_2 under control of rheostats 63, while battery B_3 provides the necessary negative grid bias for audio-frequency amplifier tubes V_3 and V_4 . The tapped resistance 64 provides an adjustable grid bias for tube V_1 .

Capacitors 65 serve to bypass high frequency currents in the well-known manner in order to prevent undesired coupling effects tending to produce sustained oscillations. Capacitors 66 serve to bypass the high-frequency currents around the primary winding of transformer P_1 , thereby preventing the radio-frequency currents from entering the audio-frequency stages.

15 A uni-control element L_1 may be provided as indicated by the dashed lines for simultaneously adjusting the variometer A, stator unit of the special condenser C, and the vernier condenser B of both tuning elements T_1 and T_2 in order to 20 provide the rough tuning adjustment for the entire receiver. To the same end the rotor element R of the special condensers C may be mechanically coupled, as indicated by dashed line L_2 , to provide gang tuning for the fine tuning adjustment. The tickler coil 52, resistance 56, and capacity 57 serve the same functions as the like 25 designated elements in Figure 4.

The tickler coil 52 may be conveniently and advantageously mounted beside the stationary coil 21 of variometer A upon the inner periphery of the insulating ring 22. In addition to the mechanical simplicity afforded by this arrangement there is the additional advantage referred to above that the coupling between tickler coil 30 and variometer is automatically varied in accordance with the variometer adjustment to provide an approach to optimum coupling at all 35 times.

A brief explanation of a procedure suitable for 40 designing our improved tuning mechanism by those skilled in the art may be of assistance in understanding the invention. The desired frequency ranges of both the coarse and the fine tuners may be arbitrarily chosen and the maximum and minimum values of the reactances of 45 the coarse tuning member may also be chosen arbitrarily with respect for practical considerations and the natural relation between such values and resonance frequency.

50 Intermediate frequencies for intermediate positions of the coarse tuner may also be chosen. The preferable procedure is, first, to divide the range of the coarse tuner into sections, each of which corresponds to the desired frequency range 55 of the fine tuner such, for example, as a band of 1500 kc., and second, to choose a suitable angular position of the coarse tuner for the minimum point of each such section. An approximate shape for the independently movable plates of 60 the fine tuning member can be estimated roughly by remembering that interleaved area is a direct function of capacity and that the total capacity of the system must vary as the square of the angular displacement of the tuning control from 65 its initial position. The rate of increase in width of the plates operated conjointly with the coarse tuning member must be a matter of trial and error unless one wishes to compute the actual capacity and inductance conditions of the coarse 70 tuning member necessary for its every position.

With the coarse tuning member in an arbitrary position, preferably the minimum point of one of the heretofore described sections, the fine tuning control may be moved through 180° and the 75 values of resonance frequency plotted against

angular displacement. If the resulting curve is not a straight line, trial and error changes in the shape of the independently movable plates may be made until the curve becomes substantially straight. Then if the frequency difference between initial and final setting does not equal that desired, the width of the plates movable conjointly with the coarse tuning member may be varied until such desired frequency range is secured. 80

A new position of the coarse tuning member 85 may then be chosen. The relation between angular displacement and frequency may be a substantially straight line but the width of the conjointly movable plates will probably have to be 90 changed in the new portion which is now being interleaved in order to secure the desired frequency range for the fine tuning member. This procedure may be repeated until the entire range of the tuning mechanism has been covered. In 95 the present invention both sets of plates of the fine tuning member are of the same shape. This requires more than ordinary care in the design of the plates of the fine tuning member and renders the design considerably more difficult, but, 100 as was explained heretofore, that is not necessary, and the procedure outlined above will secure substantially straight line frequency characteristics throughout the entire range of the tuning mechanism. The relation need be only approximately 105 a straight line since it is the primary object of the invention to secure slow and accurate tuning at the higher frequencies.

110 Although there has been described and illustrated but one embodiment of our invention, it will be apparent to those skilled in the art that many variations therefrom are possible within the contemplated scope of our invention. For example, the fine tuning member may be an inductance instead of a capacitance. Such an inductance would then be connected in series with variometer A to secure an additive relation between their inductive reactances. It is also appreciated that additive relation need not be maintained between the fine tuning device and the device of similar electrical character in the coarse tuning member. For instance, condenser C might be connected in series with condenser B. Such an arrangement, however, would unnecessarily complicate the design of the tuning mechanism. 120

125 What is claimed is:

1. A radio tuning mechanism tunable over a wide range in frequency, at a relatively slow rate of frequency change with adjustment of a tuning element thereof, comprising coarse and fine tuning members, said coarse tuning member comprising a resonance circuit tunable by a single coarse tuner control and including inductance and capacity at least one of which is variable, the fine tuning member comprising a variable tuning device included in said resonance circuit and comprising two movable elements, one said element being independently adjustable for providing fine tuning over a relatively narrow band width, the other said element being movable by said coarse tuner control for causing said fine tuner to tune over a relatively narrow band width for all settings of said control. 135

2. A unitary radio tuning mechanism tunable over a wide range in frequency at a relatively slow rate of frequency change with adjustment of a tuning element thereof, comprising coarse and fine tuning members, said coarse tuning member comprising a resonance circuit tunable over said 140

- frequency range by a coarse tuner control, said resonance circuit including inductance and capacity at least one of which is variable, said fine tuning member comprising a condenser of the 5 rotary interleaving plate type connected in shunt with said capacity and consisting of two sets of plates mounted on separate shafts, a first set being independently adjustable to provide fine tuning over a relatively narrow band width, the 10 plates of said set being shaped to vary the resonance frequency of said circuit in substantially equal increments for equal angular adjustments of said plates, the other set of plates being movable by said coarse tuner control and shaped to so 15 vary the ratio of maximum to minimum capacity due to adjustment of said first set as to permit said first set to tune over a relatively narrow band width for all settings of said coarse tuner control.
3. A slow-speed, wide range radio tuning mechanism comprising coarse and fine tuning members in combination, the coarse tuning member comprising inductance and capacity devices, at least one of which is variable, the fine tuning member comprising a variable tuning device in additive 20 electrical connection with the device of similar character in said coarse tuning member, said fine tuning member comprising two movable elements, one of said elements being operatively connected to the movable elements of said coarse tuner, the 25 inductances and capacities of said coarse and fine tuning elements being so designed and so cooperating that, for all settings of said coarse tuning member equal mechanical adjustments of said fine tuning member produce substantially equal 30 changes in a frequency characteristic of the tuning mechanism.
4. A radio tuning mechanism tunable over a wide range in frequency at a relatively slow rate of frequency change with adjustments of a tuning element, comprising coarse and fine tuning members in combination, the coarse tuning member comprising a resonance circuit including inductance and capacity devices, tunable by a single control over said frequency range, the fine tuning 40 member comprising a variable tuning device in additive electrical relation with the device of similar character of said coarse tuning member, said fine tuning member comprising two movable elements, the first of said elements being independently movable for fine tuning, the second of said 45 elements being movable by the control of said coarse tuning member to so control the electrical relations between said first and second elements that, for all positions of said coarse tuning member, equal mechanical adjustments of said first 50 element produce comparable changes in resonance of said circuit.
5. A radio tuning mechanism tunable over a wide range in frequency at relatively slow rate of frequency change, comprising in permanent unitary assembly, coarse and fine tuning members in combination, said coarse tuning member comprising a resonance circuit tunable by a single control over said frequency range and including 60 inductance and capacity, the fine tuning member comprising a variable condenser in parallel electrical relation with said capacity, said condenser comprising two movable elements, the first element being independently movable for fine tuning, the second element being movable by the control of said coarse tuning member to effect 65 positive relation between the positions of the two, said relation together with the shapes of said elements cooperating to cause equal displacements of said fine tuning element to effect 70 comparable changes in the resonance frequency of said tuning mechanism.
6. A radio tuning mechanism tunable at comparable rates of frequency change at all points over a wide range in frequency, comprising coarse and fine tuning members in combination, said coarse tuning member comprising a resonance circuit including an inductance and capacity in parallel connection, tunable over said frequency 75 range by a single control, the fine tuning member comprising a variable condenser in parallel connection with said capacity, said condenser comprising two adjustable elements, the first element being independently movable for fine tuning, the second element being movable by the control of said coarse tuning member to vary the capacity relations with respect to said first element, said relations, together with the shapes of said elements cooperating in a manner such that, for all positions of said coarse tuning member, displacement of said fine tuning member from minimum to maximum setting covers comparable frequency bands.
7. A radio tuning mechanism tunable at a relatively slow rate of frequency change over a wide range in frequency, comprising coarse and fine tuning members in combination, said coarse tuning member comprising a resonance circuit including the usual inductance and capacity elements tunable over said frequency range by a single coarse tuner control, the fine tuning member comprising a variable condenser in parallel electrical relation with said capacity, said condenser comprising two movable interleaving sets 80 of similarly shaped plates, the first set being independently movable for fine tuning, the second set being movable by the control of said coarse tuner, the relative positions of said coarse tuner elements and said second set of plates being 85 adjusted so that for all settings of said coarse tuner control, equal displacements of the control of the fine tuning member produce comparable changes in the resonance frequency of said tuning mechanism.
8. A radio tuning mechanism tunable at all points over a wide range in frequency at comparable rates of frequency change comprising, coarse and fine tuning members in combination, said coarse tuning member comprising a resonance circuit including inductance and capacity elements, tunable over said frequency range by a coarse tuner control, the fine tuning member comprising a variable condenser in parallel electrical relation with said capacity, said condenser comprising two movable interleaving sets of substantially J-shaped plates mounted in opposition upon separate shafts, the first set being independently movable for fine tuning, the second set being movable by the control of said coarse tuner, the relative positions of said coarse tuner elements and said second set of plates being so 100 adjusted that, for all settings of said coarse tuner control, equal angular displacements of said first set of plates produces comparable changes in the resonance frequency of said tuning mechanism.
9. A radio tuning mechanism tunable at a substantially uniform rate over a wide range in frequency comprising coarse and fine tuning members in combination, said coarse tuning member comprising a resonance circuit including inductance and capacity elements at least one of which is variable, the fine tuning member comprising a condenser having two movable in- 105

terleaving plate elements, the first of said elements being independently movable and so shaped that, in its cooperation with the second element, there is a substantially straight line relation between the angular displacement of said first element and the resonance frequency of said tuning mechanism, the second element being operatively connected with the control of said coarse tuning member and being of such shape that, for all settings of said coarse tuning member, displacement of the fine tuning member from minimum to maximum setting covers substantially equal resonance frequency bands.

10. In a radio tuning mechanism capable of tuning within a frequency range of from 3,000 kilocycles to 20,000 kilocycles, permanent coarse tuning means having fixed and movable elements, and fine tuning means in cooperation, said fine tuning means comprising two sets of interleaving 15 rotatable plates, the first set being movable conjointly with the movable elements of said coarse tuning means, the second set being independently

movable, said plates being so shaped that, for all positions of said coarse tuning means, equal displacements of said fine tuning means causes substantially equal changes in the resonance frequency of said tuning mechanism.

11. In a radio tuning mechanism capable of tuning within a frequency range of from 3,000 kilocycles to 20,000 kilocycles, the combination with a coarse tuning means having fixed and movable elements, of a fine tuning means comprising a variable condenser having two sets of interleaving rotatable plates, one set being movable conjointly with the movable elements of said coarse tuning means, the second set being independently movable, said plates being substantially J-shaped and so proportioned that for all positions of said coarse tuning means, equal displacements of said fine tuning means causes substantially equal changes in the resonance frequency of said tuning mechanism.
